UNITED STATES PATENT OFFICE.

WALTER R. ADDICKS, OF BROOKLINE, MASSACHUSETTS.

HEATING APPARATUS.

SPECIFICATION forming part of Letters Patent No. 634,126, dated October 3, 1899.

Application filed September 12, 1896. Serial No. 605,629. (No model.)

To all whom it may concern:

Be it known that I, WALTER R. ADDICKS, residing in Brookline, county of Norfolk, and State of Massachusetts, have invented an Improvement in Heating Apparatus, of which the following description, in connection with the accompanying drawings, is a specification, like letters and figures on the drawings representing like parts.

10 This invention relates to a heating apparatus especially designed and adapted for obtaining a high heat from the combustion of gases, whereby the said apparatus is particularly well adapted for the manufacture or production of metallic carbids employed in the manufacture of acetylene gas.

In accordance with this invention the apparatus consists, essentially, of a gas producer or generator, a converting or reducing chamber, in which is placed the materials or ingredients for forming the carbid, usually lime or calcium carbonate and coke or other carbonaceous material, and which chamber is connected with the gas-producer for the admission of gases employed in heating the materials to form or preparatory to forming the carbids, a chamber for heating the air-blast admitted into the converting or reducing chamber, and an oil-heater connected to the converting or reducing chamber for supplying oil thereto. The converting or reducing chamber may and preferably will be provided with suitable electrodes, which are connected to a dynamo or current-generator, which for the best results is driven by an engine operated by steam from a boiler, connected to the heating apparatus, as will be described, for utilizing the waste gases in generating steam, the said boiler being also preferably connected with the gas producer or generator for the production of water-gas therein, as will be described. To enable the carbids to be produced at a minimum cost and in a substantially continuous manner, I prefer to employ a plurality of reducing-chambers suitably connected to the gas producer or generator and a plurality of blast or air heaters and oil-heaters suitably connected with the reducing-chambers, so that 50 when carbid is being formed in one reducing-chamber the other reducing-chamber may be charged with the materials to be reduced

and so that one pair or set of blast and oil heaters may be heated by waste gases while the other set is being used to heat air and oil, as will be described. These and other features of this invention will be pointed out in the claims at the end of this specification.

Figure 1 represents in side elevation a heating apparatus embodying this invention; Fig. 2, a top or plan view of the apparatus shown in Fig. 1; and Figs. 3 to 6, inclusive, sectional details, to be referred to.

Referring to the drawings, A represents a gas generator or producer which may be of any suitable or desired construction and preferably provided at the opposite ends of the fuel therein with air or blast inlet pipes a' , (see Fig. 3,) steam-inlet pipes a^2 a^3 , and gas-outlet pipes a^4 a^5 , the blast-pipes a' being provided with valves a^6 a^7 , the steam-inlet pipes with valves a^8 a^9 , and the gas-outlet pipes with valves a^{10} a^{12} , substantially as shown and described in United States Patent No. 575,625, granted to me January 19, 1897.

The gas producer or generator A in accordance with this invention has its gas-outlet pipes a^4 a^5 connected to preferably two chambers B B' of any suitable construction capable of withstanding high temperatures, and in the present instance the gas-outlet pipes a^4 a^5 are represented as connected by a common outlet-pipe a^{13} (shown as a continuation of the pipe a^5) to branch pipes a^{14} a^{15} , leading, respectively, to the chambers B B', and preferably communicating with the lower ends of the same, the pipes a^{14} a^{15} being provided with suitable valves a^{16} a^{17} , controlling the admission of the gases from the producer or generator A into the chambers B B'. The chambers B B', I prefer to designate as the "converting" or "reducing" chambers, in which are placed the materials to be heated and reduced, which materials may be supposed to be calcium carbonate and coke or other carbonaceous material. The chambers B B' in practice will be provided with suitable inlets for the material, and preferably with suitable grate-bars 30. (See Fig. 4.) The reducing-chambers B B' are provided with gas-outlet pipes a^{20} a^{21} , herein represented as located near the top or upper end of the said chambers and which are preferably connected, as will be described, to two sets or pairs

of heaters or chambers C C' D D'. The chambers or heaters C C', I prefer to designate as the "air-blast heaters" and the chambers D D' as the "oil-heaters."

5 The blast-heaters C C' and the oil-heaters D D' may be of any suitable construction and preferably contain refractory baffling material, such as a checker-work of fire-brick. (See Figs. 5 and 6.) The blast and oil heaters are designed to work in pairs—that is, the blast-heater C and the oil-heater D work together or at the same time, as will be described, and the blast-heater C' and the oil-heater D' work together—and, further, both pairs work with either reducing-chamber B or B', as will be described.

10 The blast and oil heaters C C' D D' are connected to the gas-outlet pipes $a^{20} a^{21}$ for the passage through them of the waste gases, and this connection may and preferably will be effected in a manner as will now be described.

15 The gas-outlet pipe a^{20} for the reducing-chamber B is connected to the air-blast heater C near its upper end by the pipe a^{22} , provided with the valve a^{23} , and the said gas-outlet pipe a^{20} is also connected to the air-blast heater C' by the pipe a^{24} , provided with the valve a^{25} . The gas-outlet pipe a^{20} is connected with the oil-heater D by means of a pipe a^{26} , herein shown as connected to the pipe a^{22} , (see Fig. 2,) the pipe a^{26} being provided with the valve a^{27} . The gas-outlet pipe a^{20} is also connected to the oil-heater D' by the pipe a^{28} , herein shown as connected to the pipe a^{24} , the pipe a^{28} being provided with the valve a^{29} . The gas-outlet pipe a^{21} for the reducing-chamber B' is connected in a similar manner to the blast and oil heaters, it being shown as connected to the air-blast heaters C C' by the pipes $a^{30} a^{31}$, respectively, provided with the valves $a^{32} a^{33}$, the pipes $a^{30} a^{31}$ being connected to the oil-heaters D D' by the pipes $a^{34} a^{35}$, provided, respectively, with the valves $a^{36} a^{37}$. The pipe connection from the gas-outlet pipes $a^{20} a^{21}$ is made, as herein represented, at or near the top of the blast and oil heaters. The blast and oil heaters are provided at or near their bottom with gas-outlet pipes, as will now be described.

20 Referring to Fig. 2, the blast-heater C is provided at or near its bottom with two outlet-pipes $a^{40} a^{41}$ for the waste gases, provided with valves $a^{42} a^{43}$, the said gas-outlet pipes $a^{40} a^{41}$ having connected to them gas-outlet pipes $a^{72} a^{73}$ for the blast-heater C', the pipes $a^{72} a^{73}$ being provided with the valves $a^{44} a^{45}$. The gas-outlet pipes $a^{40} a^{41}$ are further connected with the oil-heaters D D' by gas-outlet pipes for the said heaters, the oil-heater D being provided with the gas-outlet pipes $a^{50} a^{51}$, connected, respectively, with the gas-outlet pipes $a^{40} a^{41}$ and provided with the valves $a^{52} a^{53}$, the gas-outlet pipes $a^{40} a^{41}$ being connected with the oil-heater D' by the gas-outlet pipes $a^{54} a^{55}$, provided with the valves $a^{56} a^{57}$. The gas-outlet pipes $a^{40} a^{41}$ preferably communicate with the lower end or fire-box

25 a^{60} of a boiler a^{61} , which may be of any suitable or usual type and herein shown as an upright tubular boiler, the pipes $a^{40} a^{41}$ being provided near the boiler with valves $a^{62} a^{63}$, and the pipes $a^{40} a^{41}$, intermediate of the boiler a^{61} , and the gas-outlet pipes $a^{54} a^{55}$ for the oil-heater D' preferably communicate with stacks or chimneys $a^{64} a^{65}$, having their upper ends normally closed by suitable valves, represented as provided with operating-levers $a^{66} a^{67}$.

30 In order to simplify the drawings, the stacks or chimneys $a^{64} a^{65}$ are represented as vertical pipes. The air-blast heaters C C' and the oil-heaters D D' are respectively provided with air-blast-admission pipes 2 3 4 5, provided with valves 6 7 8 9 and communicating with a common or main air-supply pipe 10, constituting the outlet for a blower 12 of any suitable or desired construction, the air-outlet pipe 10 having connected to it the air-inlet pipe a for the generator or producer A and being also connected, as shown, to the fire-box a^{60} of the boiler a^{61} by the pipe 13, provided with the valve 14.

35 The blast-heaters C C' are provided at or near their bottom with air-blast-outlet pipes $b b'$, (represented in the drawings as communicating with the bottom of the said heaters, at the center thereof,) the said pipes being provided with valves $b^2 b^3$ (see Fig. 1) and the pipe b being represented as connected with the pipe b' , which latter is extended by the pipe b and connected by the branch pipes $b^4 b^5$ with the bottom of the reducing-chambers B B', respectively, the said branch pipes being provided, as herein represented, with valves $b^6 b^7$. The oil-heaters D D' are provided with oil-inlet pipes $b^8 b^9$, provided with valves $b^{10} b^{12}$ and which in practice communicate with a suitable source of supply for the oil and not herein shown, and the said oil-heaters are also provided with oil-outlet pipes $b^{13} b^{14}$, provided with valves $b^{15} b^{16}$, the oil-outlet pipe b^{14} being represented as extended beyond the pipe b^{13} and communicating with branch pipes $b^{17} b^{18}$, leading into the reducing-chambers B B', preferably near their bottom, as herein shown, the branch pipes $b^{17} b^{18}$ being provided with valves $b^{19} b^{20}$. The steam-pipe a^2 communicates with the steam-space of the boiler a^{61} , the said pipe being shown as provided near the boiler with a valve b^{22} . The boiler a^{61} may have communicating with it a feed-water heater b^{23} .

40 In operation the blast-heater C and the oil-heater D are employed in conjunction with one another and with either reducing-chamber, and the blast-heater C' and the oil-heater D' are also used in conjunction with one another and with either reducing-chamber. When one reducing-chamber, as B, is being employed in manufacturing the calcium carbide, the other chamber, as B', at such time is idle and is being charged with the materials from which the carbide is made, and when the chamber B is in operation the air-blast is

heated by its passage through the heater C and passes into the reducing-chamber B, while the oil supplied to the reducing-chamber B is heated on its passage through the oil-heater D. While the reducing-chamber B is in use, the blast-heater C' and the oil-heater D' are being heated by the waste gases which pass off from the said chamber. The materials in the chambers B B' are subjected to the heat of the gases evolved or generated in the producer A, which gases may and preferably will be a mixture of water-gas and blast-gases, created by the admission of steam and air into the producer A, which contains coal or other combustible fuel. The generator or producer A is provided with blast and steam pipes and with gas-outlet pipes at the opposite ends of the fuel therein for the passage of the blast and steam in opposite directions through the fuel and for the escape of the gases thus produced into the active reducing-chamber, which may be supposed to be the chamber B. The gases from the producer admitted into the chamber B pass through the materials therein, raising the temperature of the same to a high heat, which may be increased by the admission of the heated oil, which is in a more or less gaseous state, and also by the admission of the heated air-blast. The materials in the chamber B are thus highly heated and the reduction promoted, and the gases from the chamber B, which are highly heated, pass out from said chamber through the pipes a^{20} a^{24} a^{28} , the valves a^{25} a^{29} being open, into the blast-heater C' and oil-heater D', where they may meet an air-blast admitted from the supply-pipe 10 by the pipes 3 5, the valves 7 9 being open.

The air-blast admitted into the heaters C' D' effects the complete combustion of the waste gases from the carbid-chamber B, thereby heating the interior of these heaters, and the unconsumed or waste gases pass out from the heaters C' D' by the pipes a^{32} a^{34} , the valves a^{44} a^{56} being open, into the pipe a^{40} , from whence they may pass up through the stack a^{64} to the atmosphere, or, preferably, they may pass into the fire-box a^{60} of the boiler a^{61} , where they meet a further supply of air admitted into the fire-box through the pipe 13, the valve 14 being open. The gases after passing through the boiler a^{61} and feed-water heater b^{28} pass out to the atmosphere.

From the above description it will be seen that while the chamber B is in active operation and the charge therein is being reduced into the form of a metallic carbid the air-blast supplied to the chamber B is highly heated on its passage through the air-blast heater C, and the oil supplied to the chamber B is also highly heated on its passage through the oil-heater D, and it will further be seen that while the reducing-chamber B is in use the blast-heater C' and the oil-heater D' are having their temperatures raised by the combustion of the waste gases from the said chamber. After the materials in the reducing-

chamber B have been subjected for a given time to the heat produced by the combustion of the gases admitted into the said chamber from the producer A and of the oil admitted therein from the oil-heater D the chamber B is disconnected from the producer A, the blast-heater C and the oil-heater D are cut off from the chamber B, while the blast-heater C' and the oil-heater D' are cut off from the outlet-pipe a^{20} of the chamber B and are connected with the reducing-chamber B', and the air-blast pipe 5 is cut off from the oil-heater D' by closing the valve 9. In this case the reducing-chamber B is inactive, and the carbid formed therein may be removed therefrom, while the heaters C and D are connected, respectively, with the air-blast pipe 10 and with the gas-outlet pipe a^{21} for the reducing-chamber B', the gas-outlet pipes a^{41} a^{51} for the heaters C and D being open and communicating with the boiler.

When the apparatus is in the condition just described, the gases from the producer A pass into the reducing-chamber B', where they meet the highly heated air-blast admitted through the pipe b^5 , the valve b^7 being open, and also the oils supplied to the chamber B' through the pipe b^{18} , the valve b^{20} being open, the gases passing out from the reducing-chamber B' through the pipe a^{21} and into the heaters C and D, through the pipes a^{30} a^{34} , the valves a^{32} a^{36} being open, the said gases on their passage through the heaters C and D having commingled with them the air admitted through the pipes 2 and 4, the valves 6 8 being open, which air combines with the gases in the heaters C and D and raises the temperature of the same, the waste gases from the said heaters passing out through the pipes a^{41} a^{51} , the valves a^{48} a^{53} being open, to the fire-box a^{60} of the boiler a^{61} or, it may be, to the stack a^{65} .

It will be understood that the valves located in the various pipe connections will be opened and closed to suit the conditions of the apparatus. For instance, when the direction of the run through the producer A is from the bottom toward the top of the same the air-blast valve a^7 is closed and the air-blast valve a^6 is open, the steam-valve a^9 is closed, the steam-valve a^8 open, and the gas-outlet pipe a^{10} is closed, while the gas-outlet valve a^{12} is open. When the course of the air-blast and steam is in the opposite direction—namely, down through the bed of fuel of the producer A—the valves a^6 , a^8 , and a^{12} are closed and the valves a^7 , a^9 , and a^{10} are opened. When the reducing-chamber B is in service and the reducing-chamber B' is idle, the condition of the valves controlling the said reducing-chambers and their coöperating heaters is as follows, namely: The valve a^{16} in the gas-inlet pipe a^{14} for the reducing-chamber B is open, and the valve a^{17} in the gas-inlet pipe a^{15} for the reducing-chamber B' is closed.

With the heater B in service the heaters C

and D are connected therewith, as described, and as the gases passing out from the reducing-chamber B through the pipe a^{20} do not pass through the heaters C and D the valves $a^{23} a^{27}$ in the gas-inlet pipes $a^{22} a^{26}$ for the heaters C and D are closed, it being understood that the heaters C and D have been previously raised to a temperature sufficient to heat the air-blast which is admitted into the chamber C through the pipe 2, the valve 6 being open, and which heated air-blast passes out from the heater C through the pipe b^1 , the valve b^2 being open, through the pipe b^4 into the reducing-chamber B, the valve b^6 being open. The oil-heater D having been previously raised to the desired temperature to heat the oil, the valve 8 in the pipe 4 is closed, and the gas-outlet pipes $a^{40} a^{41} a^{50} a^{51}$ for the heaters C and D have their valves $a^{42} a^{43} a^{52} a^{53}$ closed. The valve b^{10} in the oil-inlet pipe b^8 is at such time open, as is also the valve b^{15} in the oil-outlet pipe b^{18} for the heater D, the valve b^{19} in the branch pipe b^{17} being open. The gases from the reducing-chamber B pass into the blast-heater C' and into the oil-heater D' through the gas-inlet pipes $a^{24} a^{28}$, the valves $a^{25} a^{29}$ in said pipes being open, while the valves $a^{33} a^{37}$ in the gas-inlet pipes $a^{31} a^{35}$ for said heaters are closed, and the air-blast pipes 3 and 5 at such time supply air to the heaters C' D', the valves 7 and 9 in the pipes 3 and 5 being open. The gas-outlet pipes $a^{32} a^{54}$ for the heaters C' and D' have their valves $a^{44} a^{56}$ at such time open, while the valves $a^{45} a^{57}$ in the gas-outlet pipes $a^{73} a^{55}$ for the heaters C' D' are at such time closed.

When the reducing-chamber B' is in active operation, the heaters C, C', D, and D' are connected to said chamber in the manner above described with relation to the chamber B. In the heating-up process for the heaters C and D the valves 6 8 in the air-blast pipes 2 4 are open, and the valves $a^{43} a^{53}$ in the gas-outlet pipes $a^{41} a^{51}$ for the heaters C and D are at such time open, while the gas-outlet pipes $a^{40} a^{50}$ for the heaters C D at such time have their valves $a^{42} a^{52}$ closed. When the heaters C' and D' are operatively connected with the reducing-chamber B', the valves in the gas inlet and outlet pipes for the heaters C' and D' are at such time closed, while the air-blast valve 7 for the heater C' is open and the air-blast valve 9 for the heater D' closed, the valve b^3 in the outlet-pipe b' for the heater C' being at such time open, so that the heated air-blast passes through the pipe b' and the branch pipe b^5 to the reducing-chamber B'; while the oil admitted into the heater D' through the inlet-pipe b^9 , the valve b^{12} in said pipe being open, passes through the pipe b^{14} , the valve b^{16} being open, and through the branch pipe b^{18} , the valve b^{20} in the branch pipe b^{18} being open, into the reducing-chamber B'.

From the above description it will be seen that the materials in the reducing-chambers B and B' may be subjected to various tem-

peratures according to the desire of the operator—that is, the material in the chambers B and B' may be subjected to the heat produced by blast-gases alone passing from the producer A, or by water-gases alone generated in the producer A, or by a mixture of blast and water gases, and, further, to a temperature of pure oil-gas supplied from the oil-heaters D and D', or oil-gas and water-gas, oil-gas and blast-gases, or a temperature resulting from the co-operation of all, and each temperature so produced may be raised by the independent heated air-blast supplied from the heaters C and C'.

When the heating apparatus herein described is employed in the manufacture of metallic carbids, a high temperature is required, which may be obtained by bringing the mixture of water-gas and blast-gases into the chambers B and B' in the presence of oil-gases and the independent heated air-blast. A temperature resulting from the admixture of air and gases just described is deemed sufficiently high to produce metallic carbids; but if it is desired to subject the materials in the chamber B or B' to a still higher temperature this higher temperature may be obtained by means of electricity passed through the highly-heated materials. In the presence instance I have represented the chamber B as provided with electrodes f^1 and the chamber B' with the electrodes $f^2 f^3$, shown as arranged vertically within the chambers B and B' at the opposite sides of the same, and the said electrodes are respectively connected by the wires $f^4 f^5 f^6 f^7$ to the positive and negative brushes $f^8 f^9$ of a dynamo f^{10} , which may be of any usual or suitable construction and which in practice may be driven from an engine, (not herein shown,) which may be supplied with steam from the boiler a^{61} .

I prefer to employ a single producer with two reducing-chambers and their co-operating heaters, as such an arrangement enables the carbid to be manufactured in a substantially continuous manner—that is, while one reducing-chamber is in operation the other is being charged and can be brought into active operation as soon as the carbid has been formed in the first chamber; but I do not desire to limit my invention in this respect, as a single reducing-chamber and its co-operating heaters may be employed to advantage.

It will be understood that by manipulating the valves in the various pipes connected with the heaters C C' D D' each pair may be connected with the active reducing-chamber as often as desired to maintain the heat of the air and oil.

I claim—

1. In a heating apparatus, the combination of the following instrumentalities, viz: a gas-producer, a reducing-chamber communicating therewith for the admission of the gases generated in the said producer, two sets of

air-blast heaters and oil-heaters provided with valve-controlled air and oil inlet pipes respectively, a valve-controlled outlet-pipe for the said reducing-chamber connected to said heaters for the admission therein of waste gases, and pipes provided with valves connecting the said reducing-chamber with said heaters for the admission of air and oil from said heaters into said reducing-chamber, a boiler, and gas-outlet pipes for the said blast and oil heaters provided with valves and communicating with said boiler, substantially as described.

2. In a heating apparatus, the combination of the following instrumentalities, viz: a gas-producer, a plurality of reducing-chambers communicating therewith for the admission therein of the gases generated in said producer, valves controlling the admission of the gases into said reducing-chambers, a plurality of air-blast and oil heaters provided with valve-controlled inlet-pipes, valve-controlled outlet-pipes for said reducing-chambers connected to said heaters for the admission of gases therein, valve-controlled air and oil outlet pipes connecting the air and oil heaters respectively with the said reducing-chambers, and valve-controlled gas-out-

let pipes for said air-blast and oil heaters, substantially as described.

3. In a heating apparatus, the combination of the following instrumentalities, viz: a gas-producer, a plurality of reducing-chambers communicating therewith for the admission therein of the gases generated in said producer, valves controlling the admission of the gases into said reducing-chambers, gas-outlet pipes for said reducing-chambers a plurality of air-blast and oil heaters provided with valved inlet-pipes connected with the gas-outlet pipes of the reducing-chambers, and valve-controlled air and oil outlet pipes connecting said air and oil heaters respectively with the said reducing-chambers, valve-controlled gas-outlet pipes for said air-blast and oil heaters respectively, and a boiler communicating with the gas-outlet pipes of the blast and oil heaters, substantially as described.

In testimony whereof I have signed my name to this specification in the presence of two subscribing witnesses.

WALTER R. ADDICKS.
